ATTORNEY.

UNITED STATES PATENT OFFICE.

ANDREW ROBERTSON, OF PROVIDENCE, RHODE ISLAND, ASSIGNOR TO WAITE THRESHER COMPANY, OF PROVIDENCE, RHODE ISLAND, A CORPORATION OF RHODE ISLAND.

CUFF-PIN.

No. 897,407.

Specification of Letters Patent.

Patented Sept. 1, 1908.

Application filed March 4, 1908. Serial No. 419,114.

To all whom it may concern:

Be it known that I, ANDREW ROBERTSON, of Providence, in the county of Providence and State of Rhode Island, have invented 5 certain new and useful Improvements in Cuff-Pins; and I do hereby declare the following specification, taken in connection with the accompanying drawings, forming a part of the same, to be a full, clear, and exact 10 act description thereof.

The invention relates to those articles of jewelry which are known as cuff-pins and has for its object to provide a pin of this character with means for strengthening the body 15 portion of the back plate of the pin at the point where the greatest strain comes in the operation of the pin-tongue.

To that end the invention consists in the novel construction and combination of elements hereinafter described and claimed, reference being had to the accompanying drawings. 20

Figure 1 is a plan view of the back of a blank stamped out of a sheet of metal 25 from which the back plate of my improved cuff-pin is formed. Fig. 2 is a side elevation of the back plate after it has been drawn up into its complete form. Fig. 3 is a top view of the same. Fig. 4 is a sectional view on the line $x-x$, Fig. 3, on an enlarged scale. Fig. 5 is a side elevation of the front or ornamental portion of the pin. Fig. 6 is a central longitudinal section of the completed pin. Fig. 7 is a sectional view on the line 30 $y-y$, Fig. 6, on an enlarged scale. Fig. 8 is a sectional view on the line $z-z$, Fig. 6, on an enlarged scale.

Referring to the drawings, 1 represents the blank from which the back plate of the cuff- 40 pin is formed, said blank being stamped out from a strip of sheet metal by means of a suitable die and plunger. The blank is provided at one end with an enlargement 2 and at the other end with the oppositely disposed 45 lateral ears or projections 3 and the short tail-piece 4. The lateral ears or projections 3 are each provided with a forwardly extending beveled projection 5, as shown in Fig. 1, for a purpose to be hereinafter described.

The blank 1, after it has been cut from the sheet stock, is operated upon by a suitable die and plunger, which operation rolls over the enlargement 2 to form the pin-catch 6. In the same operation the lateral ears 3 are 50 bent up at right angles to the body portion

to form the hinge-members 7 of the completed pin, and the end portion of blank 1, which lies beneath said hinge members 7, is bent upward above the level of the body portion of said blank and the tail-piece 4 is bent 60 downward, thereby forming the bearing portion 8, all as shown in Fig. 2. The beveled projections 5 are provided with an outward bend 5' at their junction with the hinge-members 7 which makes the opening between 65 said beveled projections 5 wider than the opening between said hinge-members 7, as shown in Fig. 3. Mounted in the hinge-members 7 is a suitable pin-tongue 9

The front or ornamental portion of the pin 70 consists of an elliptical cup-shaped member 10, the sides of which are higher throughout their central portions 11 than at their end portions 12, as shown in Fig. 5. In assembling the two parts of the pin, the back plate 75 in its completed form, shown in Fig. 2, is placed within the cup-shaped front portion 10, and the central portions 11 of the sides of said front portion are rolled over and their edges clamped against the inner surface of 80 the body portion of the blank 1, as shown in Figs. 7 and 8.

As will be seen in Fig. 6 the ends of the central portions 11 are wrapped around the projections 5, said projections thus serving as an 85 additional means for fastening the back plate to the front portion 10.

Referring to Fig. 6, it will be seen that the right angle fulcrum point 13 of the pin-tongue 9 will, in turning said pin-tongue to closed 90 position, bear upon the top of the bearing portion 8 of the back plate and tend to force said portion downward into the cup-shaped member 10, but any such pressure will spring 95 the free end or tail-piece 4 lengthwise, so that it will impinge all the harder against the end of said cup-shaped member. As the bearing portion 8 cannot move laterally under such pressure, the tendency is for it to bend or buckle at its inner end, and this is prevented 100 by the forward projections 5.

With the above construction the cuff-pin produced is extremely strong and efficient and the necessity of bending over the ends of the front portion upon projections formed on 105 the back plate is obviated. It will be understood that the forward projections 5 may be of any desired length and shape, it being only necessary that they be of such a construction as to strengthen the body portion of the back 110

- plate at the point where said body portion is most liable to buckle from the strain of the pin-tongue when submitted to pressure, said projections serving as braces for the body portion at such point. It will also be understood that other changes may be made in the details of construction without departing from the spirit and scope of my invention as defined by the appended claims.
10. What I claim as my invention and desire to secure by Letters Patent is:
1. In an article of the class described, the combination, with a cup-shaped front portion, of a back plate secured therein, said back plate being provided with a pin-catch and a hinge-member, said hinge-member having a forwardly extending projection between said hinge-member and the body portion of said back plate.
  2. In an article of the class described, the combination, with a cup-shaped front portion, of a back plate secured therein, said back plate being provided at one end with a pin-catch and at the other end with two hinge-members, both of said hinge-members being provided with forwardly extending beveled projections between said hinge-members and the body portion of said back plate.
  3. In an article of the class described, the combination, with a cup-shaped front portion having the sides thereof higher than the ends, of a back plate provided with two hinge-members, each having a forwardly extending projection, the sides of the cup-shaped front portion being wrapped around said forward projections.

4. In an article of the class described, the combination, with a cup-shaped front portion, of a back plate secured therein, said back plate being provided with a pin-catch, 40 two hinge-members, a pin-tongue pivoted in said hinge-members, and a forward projection from each of said hinge-members, said forward projection being integral with the body portion.

45 5. In an article of the class described, the combination, with a cup-shaped front portion, of a back plate secured therein, said back plate being provided with a pin-catch and two hinge-members, said hinge-members 50 each having an outwardly and forwardly extending projection which joins the body portion of the back plate with said hinge-member.

55 6. A back plate for cuff-pins and similar articles comprising a body portion, a pin-catch and a pair of hinge-members formed integral with said body portion, and a forwardly extending projection formed integral with each of said hinge-members and with the body portion.

60 7. A back plate for cuff-pins and similar articles comprising a body portion provided with a pin-catch, a pair of hinge-members, a bearing portion in said body portion beneath said hinge-members, and a brace between 65 each hinge-member and the body portion at the forward end of said bearing portion.

ANDREW ROBERTSON.
